UNITED STATES PATENT OFFICE.

VINCENT A. SHOWALTER, OF LATROBE, PENNSYLVANIA.

METALLIC TIE AND RAIL-FASTENING.

SPECIFICATION forming part of Letters Patent No. 736,885, dated August 18, 1903.

Application filed November 26, 1902. Serial No. 132,887. (No model.)

To all whom it may concern:

Be it known that I, VINCENT A. SHOWALTER, a citizen of the United States of America, residing at Latrobe, in the county of Westmoreland and State of Pennsylvania, have invented certain new and useful Improvements in Metallic Ties and Rail-Fastenings, of which the following is a specification, reference being had therein to the accompanying drawings.

This invention relates to certain new and useful improvements in metallic ties and rail-fastenings; and the invention has for its main object to provide means whereby the rails 15 may be securely held in position on the ties without the aid of bolts passing through the fish-plates and rails and to securely fasten the fish-plates to a metallic tie.

A further object of my invention is to provide means whereby the rails may be adjusted laterally as they become worn to conform to the gage required; further, to construct a metallic tie with means for securing the fish-plates thereto and with means to retain the 25 ballast under the tie, so as to insure a more perfect road-bed.

With the above and other objects in view the invention further consists in the novel construction, combination, and arrangement 30 of parts, as will be hereinafter more specifically described, and then particularly pointed out in the claims, and in describing the invention in detail reference will be had to the accompanying drawings, forming a part 35 of this application, and wherein like numerals of reference will be employed to indicate like parts throughout the several views of the drawings, in which—

Figure 1 is a side elevation of a part of my 40 improved tie, showing the fastening means in end elevation with the rail in section. Fig. 2 is a top plan view of a part of the tie, showing the fastening in position. Fig. 3 is an underneath plan view of a part of the tie. 45 Fig. 4 is a detail perspective view of one of the fish-plates detached.

To practice my invention, I provide a metallic tie 1, which may be cast or molded and made of a desirable length, breadth, and thickness. 50 This tie is constructed with a concave corrugated underneath face 2, which extends

the length of the tie, except for the end portions 3, which form walls whereby the ballast after being tamped under the ties will be prevented from falling out or working out at 55 the end thereof. The tie is provided on its upper face each side of the rail-seats 4 with inclined teeth 5, while the fish-plates 6, which embrace the webs of the rails, have the underneath face of their base provided with 60 teeth 7, inclined in the reverse direction to the teeth formed in the upper face of the tie, whereby the teeth of the fish-plates and those of the tie intermesh or lock, as shown in Fig. 1. Pivoted to the ends of each fish-plate 6 65 are hooks 8, the hook ends of which are adapted to engage in the notches or seats 9 provided therefor in the underneath face of the tie 1 along the edge thereof. These hooks may be sprung into their position or a hole 70 may be made through the fish-plates and a bolt passed therethrough or a lug constructed on each end of the fish-plate for pivoting the securing-hooks thereto. It is desirable that the hooks project slightly below the seats or 75 notches, as they will thereby be engaged directly with the road-bed and the more securely held. When it becomes necessary to adjust the rails laterally, the fish-plates may be shifted over one notch or tooth and again tightened, 80 these teeth in practice being made close enough that a slight adjustment may be made of the fish-plates. By corrugating the underneath face of the tie and providing the end walls the ballast will be securely retained in 85 under the tie after being tamped therein.

In practice it is desirable to construct the inside plate 6 of less size than the one at the outside of the rails, so that where switch-rails are employed they may be brought up 90 close to the main rails.

While I have described the invention in detail, yet it will be observed that in practice various changes may be made in the details of construction without departing from the 95 general spirit of my invention.

Having fully described my invention, what I claim as new, and desire to secure by Letters Patent, is—

1. The combination with the tie having its 100 upper face formed with teeth and its lower face formed with notches of fish-plates en-

gaging the teeth of the said tie, and fastening means for the said fish-plates engaging the notches of the said tie.

2. The combination with the tie, of fish-
5 plates, and securing means pivoted to the
said fish-plates and engaging the tie.

3. In combination with a metallic tie having
10 teeth on its upper face on each side of the
rail-seat, fish-plates embracing the rail and
having teeth to engage the teeth on the tie,
and hooks carried by said fish-plates to en-
gage under the tie and secure the fish-plates
and rail in position, substantially as de-
scribed.

4. The combination with the tie having its 15
upper face formed with teeth and its lower
face notched, of fish-plates formed with
toothed lower faces engaging the teeth of the
said tie, and securing means for the said fish-
plates pivoted thereto and having hooked 20
lower ends engaging the notches of the tie.

In testimony whereof I affix my signature
in the presence of two witnesses.

VINCENT A. SHOWALTER.
